Inventor:

Sidney Squines

United States Patent Office.

SIDNEY SQUIRES, OF BOSTON, MASSACHUSETTS.

Letters Patent No. 61,027, dated January 8, 1867.

IMPROVED WRINGING MACHINE.

The Schedule referred to in these Letters Patent and making part of the same.

TO ALL WHOM IT MAY CONCERN:

Be it known that I, SIDNEY SQUIRES, of Boston, in the county of Suffolk, and State of Massachusetts, have invented certain improvements in Wringing Machines, of which the following is a full, clear, and exact description, reference being had to the accompanying drawings, making part of this specification, in which—

Figure 1 is an end elevation of a wringing machine, with my improvements applied thereto.

Figure 2 is a longitudinal vertical section on the line $z z$ of fig. 1.

It is well known that in the use of wringing machines of the ordinary construction the lower roll becomes worn before the upper roll, and frequently so much so as to require to be replaced by a new one. To obviate the necessity of this operation, and to provide a means whereby the position of the rolls may be reversed when the lower roll is impaired by use, is the object of my invention, which consists in pivoting to the frame of the wringer that portion of it which fits upon and is secured to the tub, whereby the rolls may be reversed without removing them from the frame; and in connection with the above, my invention consists in projecting one end of the shaft of each roll beyond the frame, and so forming it as to receive a crank, by which the lower roll may be turned.

To enable others skilled in the art to understand and use my invention, I will proceed to describe the manner in which I have carried it out.

The sides of the framework A are secured together by means of connecting-rods B and pins a , and are provided with slots b for the reception of the ends of the shafts C D of the rubber rolls E F, the slots being made of sufficient size to allow the ends of the shafts to move up and down freely therein, one end of each shaft projecting out beyond the framework, and being provided with a screw-thread, c , by which construction, when the lower roll is impaired from use, the upper roll may be substituted therefor, and a crank may be applied thereto in a convenient and expeditious manner. The sides of the frame are open from without to receive and obtain ready access to the mechanism which regulates the pressure upon the clothes as they are passed between the rolls. Between each end of the shafts and the top and bottom of each side of the frame are placed two metal plates, $d e$, between which is placed a block of rubber, which serves as a spring, f , which is compressed by turning down a screw, G, which passes through the top or bottom of each side of the frame A, and bears against the plate d , the inside of the screw G being bored out to fit over a stud or projection, g , (see fig. 2,) formed on the plate e , which bears on the end of each of the shafts, by which means the plates $d e$ and spring f are kept in place as the upper roll is pressed down upon the clothes. Near the centre of the outer edge of each side of the frame is pivoted at h the upper ends of the portion H of the frame which fits upon the edge of the tub, and to which it is secured by tightening the screw I. After each portion, H, is swung over, it is keyed in place by means of a long rod, J, the extremities of which are bent, and pass through holes i in the side of the frame A, and into holes j formed in the portion H; this rod, J, being kept in position by being sprung under a projection, k , of the frame. By the above-described construction, when the lower roll is worn by use, the portions I may be swung over on their pivots, h , to the position seen in red, fig. 1, when the upper roll is brought underneath, and the crank attached thereto in a convenient manner, thereby avoiding the necessity of removing the pins a , and taking the rolls out of the frame.

Claim.

What I claim as my invention, and desire to secure by Letters Patent, is—

Pivoting the portions H to the frame A, so that their position can be reversed for the purpose described.

I also claim, in combination with the above, projecting one end of both shafts C D of a wringing machine beyond its frame, so that when the portions H are reversed, and the position of the rolls thereby changed, the crank may be applied to the lower shaft, as and for the purpose set forth.

SIDNEY SQUIRES,
